UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SHADE-SUPPORTING DEVICE.

1,225,397.

Specification of Letters Patent.

Patented May 8, 1917.

Application filed November 22, 1918. Serial No. 802,507.

To all whom it may concern:

Be it known that I, REUBEN B. BENJAMIN, a citizen of the United States, residing at Chicago, in the county of Cook and State 5 of Illinois, have invented new and useful Improvements in Shade-Supporting Devices, of which the following is a full, clear, concise, and exact description, reference being had to the accompanying drawing, forming 10 a part of this specification.

My invention pertains to shade supporting devices for use in connection with electric lamp sockets and it is the principal object of my invention to improve upon the existing forms of such devices. It is a further object of my invention to provide a shade support that can readily and quickly be placed on a socket, in a position for use, or removed therefrom, as desired; and that 15 is economical to manufacture, easily assembled and efficient in use. Additional objects and advantages of the invention will be apparent from the following specification, taken in connection with the appended 20 claims.

A shade supporting device constructed in accordance with my invention, I have disclosed, by way of example, in the following description and accompanying drawings, in 25 which:

Figure 1 is a side elevation showing a shade supporting device constructed in accordance with my invention attached to a lamp socket, the shade being shown in cross 35 section;

Fig. 2 is an enlarged cross sectional view taken on the line 2—2 of Fig. 1, looking in the direction of the arrows;

Fig. 3 is a cross sectional view taken on the 40 line 3—3 of Fig. 2, looking in the direction of the arrows, showing the cam ring in open position;

Fig. 4 is a similar view, showing the cam ring in locking position;

Fig. 5 is a plan of the shade supporting 45 device from below;

Fig. 6 is a detail elevation showing one of the spring tongues; and

Fig. 7 is a detail section on the line 7—7 of 50 Fig. 5, looking in the direction of the arrows.

Like reference characters refer to like parts throughout the following specification and the several figures of the accompanying 55 drawings.

Referring now to the drawings, 8 designates a shade supporting ring adapted to be attached to a lamp socket 9 having a bead 10. The supporting ring 8 has a number, in this case four, of lugs 11 spaced about its 60 periphery. These lugs 11 are adapted to pass through slots 12 in the shade 9^a whereupon they are crimped down over the shade, as shown in Fig. 1, thereby holding the shade 65 in place.

Formed integral with the supporting ring 8, so as to extend upwardly therefrom, are a plurality of spring tongues 13. In the construction shown in the drawings there are three of these spring tongues. Each of the 70 spring tongues 13 is bent so as to form a groove 14 near its upper end, the groove 14 conforming in shape to the bead 10 of the lamp socket. Just below the groove 14 the metal of the spring tongues 13 is struck inwardly to form a projection 15. By means of the groove 14 and projection 15 it will be seen that the tongues 13 will embrace the bead 10 when the device is placed on the socket. The upper ends of the spring 80 tongues 13 are bent outwardly to form horizontal lugs 16.

Rotatably mounted on the shade supporting member 8 and embraced by the lugs 16 is a ring 17, for effecting the movement of the 85 tongues 13 into supporting position. The upper part of the ring 17 is bent over inwardly to form a flange 18. The inner edge of the flange 18 is cut so as to form a plurality of spiral cam portions 19. The number of cam portions corresponds to the number of spring tongues, so that in the embodiment of my invention here described there are three of these cam portions. The ring 17 90 is of such dimensions that when mounted upon the supporting member 8 the cam portions may be made to engage projections 95 formed on the spring tongues 13. It will be seen that when the ring 17 is rotated in a contra-clockwise direction the cam portions 100 19 will force the tongues 13 inward; whereas, when the ring 17 is rotated in a clockwise direction, the tongues 13 will be permitted to move outwardly by reason of their resiliency. One of the cam portions 19 is 105 cut to form a plurality of detents 21 corresponding in size to the projection 20 on the tongue 13. It will be seen that the engagement of these detents 21 with the projection 20 will serve to hold the ring 17 in any posi- 110

tion to which it may be rotated. To limit the extent of rotation a stop 22 is formed on the ring 17 in such position that it strikes a lug on the supporting member, hereinafter to be described, when the ring 17 is at the extreme open or extreme locked position.

The ring 17 is formed at its lower edge with an outwardly flaring flange 23. Bearing on this flange 23, thereby holding the 10 ring 17 in place, are a plurality of upwardly extending lugs 24 formed integral with the supporting member 8. This method of construction forms a very simple and economical mode of mounting the ring rotatably on the 15 supporting member. These lugs 24 are the lugs above mentioned against which the stop 22 strikes to limit the rotation of the ring.

It will be seen that this shade supporting device comprises a two piece structure so 20 that it is not only extremely economical to manufacture but in addition it is very readily assembled. The flange 18 of the ring 17 is cut away, as at 25, at points to correspond with the lugs 16 of the tongues 25 13. To assemble the two parts, the lugs 24 being comparatively straight, so as to escape the flange 23, the ring 17 is slipped onto the member 8. The lugs 24 are then bent inwardly to engage the flange 23 and the 30 device is ready for use.

In the use of the device the ring is turned in a clockwise direction until it is in the open position, illustrated in Fig. 3. In this 35 position of the parts the tongues are in their extreme outward position and the device may readily be placed on the socket. By virtue of the grooves 14 and the projections 15, the tongues 13 embrace the bead 10 of the socket and the device is held in place 40 thereby. To clamp it securely in supporting position the ring 17 is then turned in a contra-clockwise direction and the cam portions 19 coming into engagement with the projections 20 force the tongues 13 inwardly 45 until the device is firmly secured in place. As before mentioned the engagement of the detents 21 with the projection 20 holds the ring in the position to which it is rotated.

To remove the device it is only necessary to 50 rotate the ring in a clockwise direction so that the cam portions will be moved away from the tongues 13 and permit the latter to spring outward, whereupon the device may be readily pulled off the socket.

Having thus described my invention what I claim as new and desire to secure by Letters Patent is:

1. The combination with a lamp socket having a bead, of a shade supporting device 60 including a shade supporting member, a plurality of spring tongues formed thereon and adapted to embrace said bead, a rotatable ring having a plurality of spiral cams thereon adapted to engage said tongue and force 65 them against the bead when the ring is ro-

tated, and a plurality of flexible members on said supporting member adapted to be bent into engagement with said ring to hold the same in place.

2. The combination with a lamp socket 70 having a bead, of a two piece shade supporting device including a member having means associated therewith for supporting the shade, a plurality of spring-tongues on said member, said tongues having means for embracing said bead, a rotatable ring mounted on said supporting member and having on its upper inside edge a plurality of spiral cams adapted to be brought into engagement with said spring-tongues to press the 80 same against said bead when the ring is rotated.

3. The combination with a lamp socket having a bead, of a two piece shade supporting device including a shade supporting 85 member having thereon a plurality of spring-tongues, said tongues having longitudinal grooves formed therein and vertically struck-in portions below said grooves, whereby said tongues embrace said bead, a 90 rotatable ring mounted on said supporting member and having on its upper edge a plurality of spiral cams adapted to be brought into engagement with said spring-tongues to press the same against said bead when 95 said ring is rotated.

4. The combination with a lamp socket having a bead, of a shade supporting device including a shade supporting member, a plurality of spring-tongues formed thereon and adapted to embrace said bead, a rotatable ring having a plurality of spiral cams thereon adapted to engage said tongues and force them against the bead when the ring is rotated, said tongues having a portion 100 bent outward to embrace said ring, and a plurality of flexible members on said supporting member adapted to be bent into engagement with said ring to hold the 105 same in place.

5. The combination with a lamp socket having a bead, of a shade supporting device including a shade supporting member, a plurality of spring-tongues on said member and adapted to embrace said bead, a rotatable ring having a plurality of spiral cams thereon adapted to engage said tongues and force them against the bead when the ring is rotated, said tongues having a portion 110 bent outward to embrace said ring, a plurality of lugs on said supporting member bearing on said ring to retain the same in place, and a stop on said ring adapted to engage said lugs to limit the extent of rotation of the ring.

6. In a shade supporting device, the combination with a lamp socket having a bead, of a shade supporting member having connected therewith a plurality of upwardly extending spring-tongues, said tongues hav- 125 130

- ing grooves formed therein whereby the tongues embrace said bead, flanges formed on the upper ends of said tongues, a rotatable ring embraced beneath said flanges, 5 a plurality of spiral cams on said ring engaging said tongues when the ring is rotated, and a plurality of lugs on said shade supporting member for retaining said ring in place.
- 10 7. In a device of the class described a shade, and means for securing said shade to a socket comprising a plurality of upwardly extending spring tongues for bearing on said socket and having free upper ends, 15 and means for forcing the upper ends of said tongues inwardly comprising a cam ring of sheet material having spiral cam portions for acting on said spring tongues, and a thumb ring for rotating said cam 20 portions, said cam portions being formed on an edge of said sheet material, and said thumb ring being formed integral with said cam portions and extending downwardly therefrom and surrounding said spring 25 tongues.
8. In a device of the class described a shade, and means for securing said shade to a socket comprising a plurality of upwardly extending spring tongues for bearing on said socket and having free upper ends, 30 and means for forcing the upper ends of said tongues inwardly comprising a cam
- ring of sheet material having spiral cam portions for acting on said spring tongues, and a thumb ring for rotating said cam portions, said cam portions being formed on an edge of said sheet material, and said thumb ring being formed integral with said cam portions and surrounding said spring tongues. 35
9. In a device of the class described a shade, and means for securing said shade to a socket comprising a plurality of upwardly extending spring tongues for bearing on said socket and having free upper ends, 40 and means for forcing the upper ends of said tongues inwardly comprising a cam ring of sheet material having spiral cam portions for acting on said spring tongues, and a thumb ring for rotating said cam 45 portions, said cam portions being formed on an edge of said sheet material, and said thumb ring being formed integral with said cam portions and surrounding said spring tongues. 50
- 55

In witness whereof, I have hereunto subscribed my name in the presence of two witnesses:
